UNITED STATES PATENT OFFICE.

DANIEL J. MURPHY, OF ST. PAUL, MINNESOTA.

EGG PRESERVER.

Application filed February 26, 1921. Serial No. 448,183.

To all whom it may concern:

Be it known that I, DANIEL J. MURPHY, a citizen of the United States, residing at St. Paul, in the county of Ramsey and State 5 of Minnesota, have invented a new and useful Egg Preserver, of which the following is a specification.

The device forming the subject matter of this application is adapted to hold a plurality of eggs during the application of a preservative to the eggs.

The invention aims to provide novel means whereby many eggs may be held in compact relation to receive a preservative, 15 such as water glass, it being possible to treat a maximum number of eggs, with a minimum amount of preservative.

Another object of the invention is to improve the device by so constructing it that 20 the egg supporting platforms may be taken out readily for cleaning.

It is within the province of the disclosure to improve generally and to enhance the utility of devices of that type to which the 25 invention appertains.

In the accompanying drawings:—

Figure 1 shows in longitudinal section, a device constructed in accordance with the invention; Figure 2 is a cross section on the 30 line 2—2 of Figure 1; and Figure 3 is a fragmental cross section, taken through one of the supports.

In carrying out the invention, there is provided a receptacle, denoted generally by 35 the numeral 1, the receptacle including a bottom 2, a shell 3 and a removable lid 4. The lid 4 may be supplied with a handle 5 and there are handles 6 on the shell 3.

Located within the receptacle 1 are any 40 desired number of supports, designated generally by the number 7. Each support 7 preferably comprises a trough-shaped member 8 having oppositely extended flanges 17, the trough-shaped members 8 being cut 45 away at their outer edges, as shown at 9, to define vertically spaced shoulders 10. The lower ends of the supports 7 rest on the bottom 2. At their upper ends, the supports 7 are supplied with tabs 18 attached by securing elements 19 to the shell 3 of the receptacle 1.

Any desired number of platforms 11 are provided. The platforms 11 are equipped with peripheral notches 12 adapted to permit the passage of the shoulders 10, when 55 the platforms 11 are moved downwardly in

the receptacle 1. When the platform 11 has arrived at the desired place, the platform is rotated, until, as shown in Figure 2, the notches 12 are out of alignment with the shoulders 10, whereupon the platform will be supported on the shoulders. Each platform 11 is provided with any desired number of openings 14, in which the eggs to be treated may be placed. The platform has, 60 further, a central opening 15, wherein no egg is placed, the opening 15 being unencumbered, to facilitate the circulation of the preservative in the receptacle 1, between the platforms 11. At their edges, the platforms 65 11 are spaced, from the shell 3 to facilitate the circulation of the preservative.

It is obvious that the device forming the subject matter of this application may be taken apart readily, for cleaning, and that 70 the preservative can circulate freely. The flanges 17 on the supports 7 exercise a double function. First, they give the supports a bearing on the shell 3, and, secondly, they space the periphery of the platform 11 from 75 the shell 3, so that there is room for the preservative to circulate between the edge or periphery of the platform and the shell.

The inner edges of the parts 8 slant outwardly, from each shoulder to the platform 85 next therebeneath. Consequently, the openings 14 may be located close to the edge or periphery of the platform, thereby increasing the capacity of the platform, and, when the platform is rotated, to align the notches 90 12 with the shoulders 10, the eggs which are in the outermost openings will not strike against the inwardly projecting parts 8.

Having thus described the invention, what is claimed is:

A device of the class described, comprising 95 a receptacle, supports in the receptacle, each support including a U-shaped double-walled portion, which is cut away to define shoulders, the constituent walls of the U- 100 shaped member being prolonged to form lateral flanges, and platforms mounted on the shoulders, the platforms having egg-receiving openings, the platforms being provided with peripheral notches permitting the 105 platforms to be adjusted vertically when the notches are aligned with the shoulders, the flanges being interposed between the receptacle and the platforms and serving to space the platforms at their periphery from the 110 receptacle, the inner edges of the supports slanting outwardly from each shoulder to

the platform next therebeneath, thereby to permit the openings to be located close to the periphery of each platform, the platforms being rotatable without causing the eggs in the outermost openings to strike the supports.

In testimony that I claim the foregoing as

my own, I have hereto affixed my signature in the presence of two witnesses.

DANIEL J. MURPHY.

Witnesses:

JAMES SCHOONMAKER,

Wm. F. HUNT.
